BAR JOIST

Julius A. Clauss, Detroit, Mich., assignor to Great Lakes Steel Corporation, Ecorse, Mich., a corporation of Delaware

Application April 5, 1938, Serial No. 200,214

5 Claims. (Cl. 189—37)

This invention relates to bar joists and the principal object is the provision of a joist of this type that is light in weight in comparison to its strength, that is simple, cheap and economical to build and use.

Other objects of the invention include the provision of a bar joist of all metallic construction to the upper and lower faces of which it is possible to secure other parts by nailing them directly thereto; the provision of a bar joist having upper and lower chords formed from angle sectioned members arranged in back-to-back relationship, the inner marginal edges of the opposed flanges being flared or flanged outwardly to provide a groove or recess therein for reception of the bar or web; the provision of a bar joist of the type described in which the web comprises a continuous bar bent to zig-zag form and alternately engaged by the upper and lower chord members and having an extended end portion engaged in the groove or recess of the upper chord member over the end portion thereof and in turn having a bearing plate welded to its lower face; the provision of a bar joist structure including upper and lower chords each of which is formed from a pair of angle section members arranged in back-to-back relationship, the opposed faces of the members of each chord being spaced from one another, the web of the joist comprising a zig-zag bar member of greater diameter than the spacing of the opposed flanges of the chord members, and the cooperating marginal edges of the opposed flanges of the chord members being bent outwardly to stiffen such flanges and to provide a groove or pocket for reception of the cooperating portions of the web; and the provision of a bar joist of the type described in which the opposed flanges of the chord members are not only spaced from one another but are complementarily curved to provide a sinuous nail receiving groove between them.

The above being among the objects of the present invention the same consists in certain novel features of construction and combinations of parts to be hereinafter described with reference to the accompanying drawing, and then claimed, having the above and other objects in view.

In the accompanying drawing which illustrates a suitable embodiment of the present invention and in which like numerals refer to like parts throughout the several different views,

Fig. 1 is a partially broken side elevational view of a bar joist constructed in accordance with the present invention;

Fig. 2 is an enlarged transverse sectional view taken on the line 2—2 of Fig. 1;

Fig. 3 is a still further enlarged transverse sectional view taken on the line 3—3 of Fig. 1.

The bar joist shown in the drawing and constructed in accordance with the present invention includes upper and lower chords indicated generally at 10 and 12, respectively, and an interconnecting web indicated generally at 14. In the particular construction shown the upper chord 10 is of greater length than the lower chord 12, its ends projecting longitudinally beyond the corresponding ends of the lower chord 12 so as to adapt the joist for support from the upper chord.

Broadly speaking the chords 10 and 12 follow the teaching disclosed and claimed in United States Letters Patent to Buelow, et al. No. 1,900,541 and particularly to the form of the half stud disclosed therein. In other words each of the chords 10 and 12 is made up of a pair of angle sectioned members and the corresponding flanges of these members are arranged in back-to-back but generally spaced relationship with respect to each other, and the surfaces of the remaining flanges are arranged in coplanar relationship. Those flanges which are arranged in back-to-back and spaced relationship are complementarily curved and the spacing between them is such as to provide a sinuous nail receiving slot or groove 20 between them.

The two angles 16 and 18 are rigidly secured together by means of boss-like projections 22 formed at intervals in one of the curved flanges and which bear against the curved flange of the other angle member to which they are suitably secured as by welding, riveting, or the like. The bosses 22 also serve to accurately space the curved flanges from one another so as to provide a nail receiving groove or recess 20 of uniform width throughout the length of the chord. The angle members are further rigidly spaced and secured together by welding to the web 14 as will hereinafter be described.

The use of the above described type of chords 10 and 12 permits the nailing of cooperating material directly to the upper and lower faces of the joist. Such material may obviously be flooring, lathe, sheet material of any desired type or description, or the like. For the purpose of illustration a section of wooden flooring 24 is illustrated in Figs. 1 and 2 as being applied to the upper surface of the upper chord shown in these figures, the flooring 24 being secured in place by means of nails 26 driven down through the floor-

ing into the nail receiving grooves 28 as illustrated in Fig. 2. As more fully described in the above identified Buelow et al. patent, this construction provides means whereby such material as the flooring 24 may be readily nailed directly to the angle members 16 and 18 by the usual types of nails which will hold the material 24 to the angles with much greater security than is usually possible where the nails are driven through the material 24 and into woods commonly used in construction purposes.

The angle members 16 and 18 are preferably formed from sheet material and rolled or bent to angular shape and the gauge of the material from which they are formed may, of course, be sufficient to obtain the desired strength in the completed joist. In order to stiffen the chords 10 and 12 against distortion under load, it has been found preferable, in accordance with the present invention, to inwardly flange the free marginal edges of the horizontally extending flanges of the angle members 16 and 18 as best illustrated at 28 in Fig. 3, this permitting the use of a lighter gauge stock in the angle members than would otherwise be possible.

To further stiffen the angle members 16 and 18 against distortion in a lateral direction as well as to provide a seat for the web 14 therein, the free marginal edges of those flanges of the angles 16 and 18 arranged in back-to-back relationship are outwardly curved or flanged as best illustrated at 30 in Fig. 3 so as to form a preferably longitudinally continuous groove or pocket 32 between such marginal edges the cross-sectional curvature of which is approximately complementary to the exterior curvature of the web 14.

The web 14 may be made up of one or more bar elements and arranged in zig-zag relation between the chords 10 and 12. Preferably the web 14 is made from a single continuous bar which may be of any desired cross-sectional configuration but for the purpose of simplicity is preferably round as shown and of a diameter substantially greater than the width of the nail receiving groove 28 so that the groove 32 will offer positive shoulders interiorly thereof for contact with the web 14. The bar from which the web 14 is formed is bent into zig-zag relationship illustrated in Fig. 1 with the bights of the loops preferably flattened off as at 34 to provide a horizontally extending surface of material length at the points where the web 14 is received in the pocket 32. The web 14 and the angles 16 and 18 of each of the chords 10 and 12 are preferably suitably welded or otherwise secured together at their areas of contact, resistance welding having been found suitable for this purpose.

The zig-zag bar web 14 is preferably so constructed and arranged that the outermost run thereof at each end extends upwardly from the corresponding end of the lower chord outwardly toward but materially short of the corresponding end of the upper chord, and at the point where it meets the upper chord such end is bent horizontally into parallelism with such upper chord as at 36 and is received within the groove or pocket 32 at such end and is firmly welded therein. A bearing plate 38 which may be relatively heavy plate of metal of rectangular cross-sectional configuration is positioned with the plane of thickness in a horizontal relation below and in contact with each extended end 36 and it is suitably and rigidly welded thereto as indicated at 40 in Fig. 3. As illustrated in Fig. 1 the bearing plates 38 are preferably of a length greater than the corre-

sponding ends 36 and the inner end of each plate is, therefore, bifurcated for reception of the last corresponding run of the web 14 so as to bring the outer end of the bearing plates 38 flush with the corresponding outer ends of the upper chord 10 as illustrated. Accordingly, it will be observed that with this construction the last or outermost runs of the web 14 have their end portions interposed between the bearing plates and the corresponding end of the upper chord 10 which thus positively ties in the outer end of the lower chord to the corresponding end of the outer chord so as to positively transmit the load between the two chords at their ends.

From the foregoing it will be appreciated that because of the spacing of the angles 16 and 18 to provide a nail receiving slot between them not only is it possible to directly nail flooring, lathing, or the like directly to the joist but the spacing of the angles and their rigid securing to one another stiffens the structure against lateral distortion. Furthermore, the provision of the groove or pocket for reception and securing of the web 14 provides in effect laterally projecting flanges which, together with the flanges 28 at the outer margin of the faces of the angle members 16 and 18, materially enhances the strength of the structure against both lateral and vertical distortion. It will also be appreciated that this feature provides a bar joist of maximum strength for the amount of material employed in its construction, thus making the construction economical to use and that the construction as a whole, because of its simplicity, is economical to produce.

Formal changes may be made in the specific embodiment of the invention described without departing from the spirit or substance of the broad invention, the scope of which is commensurate with the appended claims.

What is claimed is:

1. A bar joist comprising a pair of chord members and an interposed web member, each of said chord members comprising a pair of angle members arranged in back-to-back and generally spaced relationship, those flanges of said angle members arranged in back-to-back relationship being complementarily curved to form a sinuous nail receiving groove between them, the free marginal portions of said curved flanges of each chord being outwardly bent away from one another to form a groove extending longitudinally of said chord therebetween, and a web including a zig-zag bar member positioned with the consecutive bights thereof received alternately in the pockets of said chord members and secured therein.

2. In a bar joist, in combination, upper and lower chords and a web interconnecting the same, said chords each comprising a pair of angle members secured together in back-to-back and generally spaced relationship so as to afford a fastener receiving groove between them, the free marginal edge portion of those flanges of said angle members in back-to-back relationship being outwardly bent with respect to each other to form a groove therebetween, a zig-zag bar web having its bights alternately received and secured in the groove of the upper and lower chords, an outermost run of said web extending upwardly from the lower of said chords and outwardly therefrom towards the corresponding end of the upper of said chords and having a longitudinally extending end portion received and welded in said groove in the upper of said chords, and a bearing member secured to said end portion.

3. In a bar joist, in combination, an upper chord and a lower chord each comprising a pair of angle members arranged in back-to-back relationship, the free marginal edge portions of said flanges arranged in back-to-back relationship being bent outwardly with respect to each other to provide a longitudinally extending groove, a zig-zag bar web member arranged between said chords with the bights thereof received within said grooves and secured thereto, said upper chord extending longitudinally beyond the corresponding ends of the lower of said chords, and the end runs of said web member extending from the corresponding end of said lower chord upwardly and outwardly towards the corresponding end of the upper of said chords and terminating in a longitudinally extended end portion received within the groove of said upper chord and secured thereto, a bearing plate at each end of said joist having a bifurcated end portion receiving the last run of said web at the corresponding end of said joist disposed below the corresponding said extended end portion of said last run and welded directly thereto.
4. In a joist, in combination, upper and lower chords each comprising a pair of members arranged in generally spaced back-to-back relationship so as to provide a fastener receiving
- groove between them, at least one member of each said pair being formed to provide a flange for the corresponding chord, the free marginal edge portions of said members extending outwardly away from each other to form pockets therebetween, and a web member extending between and spacing said chords, said web member comprising a bar bent to zig-zag formation with the bights thereof received and secured in said pockets.
5. A joist comprising upper and lower chords each comprising a pair of members arranged in generally spaced back-to-back relationship so as to provide a fastener receiving groove between them, at least one member of each said pair having a laterally extending flange, the marginal edge whereof is bent into angular relationship with respect thereto whereby to stiffen the corresponding chord against vertical distortion, the free marginal edge portions of said members being outwardly bent to form a longitudinally extending groove therebetween whereby to stiffen said flanges against lateral distortion and to provide web receiving pockets, and a bar web extending between said chords and received and secured in said pockets.
